UNITED STATES PATENT OFFICE.

TIMOTHY G. PALMER, OF SCHULTZVILLE, NEW YORK.

TORPEDO RAILWAY-SIGNAL.

SPECIFICATION forming part of Letters Patent No. 310,717, dated January 13, 1885.

Application filed January 21, 1884. (No model.)

To all whom it may concern:

Be it known that I, TIMOTHY G. PALMER, of Schultzville, in the county of Dutchess and State of New York, have invented an Improvement in Torpedo Railway-Signals, of which the following is a specification.

This danger-signal is intended to be used on railways to indicate at the main track when a switch is opened to a siding or branch, and it is so designed to work automatically, so that it receives motion from the mechanism that moves the switch, in order that simultaneously with the opening of the siding, switch, or other source of danger the torpedo may be brought into position to be exploded, and is removed from that position when there is no longer any danger. It is to be understood that the torpedo-signal is to be placed at a sufficient distance from the switch to allow the train to be stopped before reaching the open switch or other danger. I make use of an anvil, an exploder above the same, to be acted upon when elevated by the passing wheels, a torpedo magazine or holder, and a slide that receives the torpedo and moves it back and forth each time the slide is moved by its connection to the switch, and a cam-lever between the slide and the exploder to raise the latter and prevent it interfering with the torpedo when being moved back and forth. The torpedo-holder is below the level of the track, so as not to be injured by any passing device, such as a cow-catcher or snow-plow.

In the drawings, Figure 1 is a central vertical section longitudinally of the slide. Fig. 2 is a plan of the apparatus. Fig. 3 is an inverted plan of the cover. Fig. 4 is a cross-section through the anvil at the line $y-y$, the exploder being in elevation. Fig. 5 is a vertical section at the line $x-x$, showing the cam-lever to the exploder; and Fig. 6 is a separate plan view of the forked end of the slide.

The base a is provided with an anvil, b , at one end, and above this base is a movable cap, c . The base is to be suitably supported and attached to the rail. I prefer to use the clip-plate d , that passes under the rail f and has a lip, d' , that hooks over the flange of the rail, and the parts are held together by bolts h , that pass through lugs upon the cap and base and through the clip-plate.

In the base a there is a tubular torpedo

magazine or holder, k , extending down any desired distance, so as to hold the required number of torpedoes, and to be entirely out of the way of snow-plows or cow-catchers; hence said holder can be comparatively close to the rail, and the torpedo has to be moved but little distance from the holder to the anvil b . Within this holder there is a spring, g , that tends to lift the torpedoes, and there is an opening through the cap c provided with a removable flanged plug, l , that is held down by a screw-thread or bayonet-lock pins, so as to be removable for the insertion of the torpedoes. The flange of the plug prevents water passing in around the plug, and the spring g should be limited in its upward movement, so as not to interfere with the slide, herein-after described, when the torpedoes are exhausted from the holder. This may be accomplished by the end of the spring passing off laterally into a vertical groove in the inside of the torpedo-holder, the upper end of such groove being closed to form a stop to the end of the spring. The slide m is introduced between the base a and the cap c into a space provided for it, wherein it is free to be moved endwise by the rod n , that is at the back end, and is connected to the switch mechanism or other device for moving the torpedo automatically. At the forward end there is an opening, p , adapted to receive the torpedo i , and the end is forked and undercut at the edges, as shown, and the anvil is comparatively narrow. This slide receives into the opening p a torpedo, i , and moves it back and forth every time the slide is moved; but if the torpedo is fired by the exploder r being forced down upon it, the parts of the torpedo-case are separated and escape downwardly and sidewise at the sides of the anvil and below the beveled forked end of the slide, so that the slide is drawn back empty and ready to receive another torpedo when the opening in the slide arrives at the magazine. The exploder r is in the form of a plug passing through a hole in the cap c , and provided with a head and rim to prevent water running down the sides of the exploder, and this exploder has to be raised so that the torpedo can pass back and forth under it, but the top of the exploder is sufficiently high above the rails when the torpedo is beneath it to be forced down by the

passing locomotive or car wheels and explode the torpedo. When the torpedo is not beneath the exploder, the latter should be lowered down, so as to be out of the way of the wheels.

5 A convenient device for raising and lowering the exploder is the forked levers *o* let into grooves or recesses in the under side of the cap *c*, and acting against a cross-pin, *t*, in the exploder. The cam projections *s*, upon the levers *o*, enter recesses in the surface of the slide when the latter is fully moved toward the rail, so that the levers *o* lie upon the slide *m* and the exploder is free to be forced down; 10 but as the slide draws back it underruns the cams *s* upon the levers *o*, and raises such levers and holds up the levers and the exploder. At the ends of the slide *m* there are cam-surfaces *s'*, that act upon the cams *s* to raise the levers *o*, and the exploder when the torpedo is being moved under the exploder. At the extreme movement backwardly of the slide *m* the exploder rests upon the anvil. When the slide *m* is moved forward toward the rail, the 15 exploder is first lifted by the inclines *s'* sufficiently for the cartridge to be pressed in beneath it.

I claim as my invention—

1. The combination, in a danger-signal, of 30 an anvil upon which the torpedo can be exploded, a slide to move the torpedo, an exploder, a cap for holding the same, and a cam-

lever acted upon by the slide for raising the exploder before passing the torpedo under it, substantially as specified.

35

2. The combination, in a danger-signal, of a slide connected with a switch or other moving device, a torpedo-holder placed below the slide and below the level of the track, an anvil, an exploder, a cap to hold the exploder 40 and to cover the slide, and a lever or cam between the slide and the exploder to raise the exploder before passing the torpedo beneath it, substantially as specified.

45

3. The slide receiving an endwise movement and having a jaw for receiving the torpedo, in combination with an anvil upon which the torpedo rests, an exploder, a lever receiving its motion from the slide and by which the exploder is raised or lowered, and a cap 50 covering the slide, substantially as specified.

4. The combination, with an anvil, of a torpedo-magazine below the anvil, a spring to raise the torpedoes, a slide for receiving such torpedoes, an exploder, a cap covering the 55 slide and provided with an opening for the insertion of the torpedoes, and a cover for such opening, substantially as specified.

Signed by me this 11th day of January, A. D. 1884.

T. G. PALMER.
